DESIGN.

F. H. SCHAFFER.

BROOCH PIN OR SIMILAR ARTICLE OF JEWELRY.

APPLICATION FILED APR. 17, 1918.

52,228.

Patented July 23, 1918.

*Inventor
Frank H. Schaffer*

by his attorney G. A. Bourne

UNITED STATES PATENT OFFICE.

FRANK H. SCHAFFER, OF PROVIDENCE, RHODE ISLAND, ASSIGNOR TO THE IVORYLOID CO., INC., OF NEW YORK, N. Y., A CORPORATION OF NEW YORK.

DESIGN FOR A BROOCH-PIN OR SIMILAR ARTICLE OF JEWELRY.

52,228.

Specification for Design.

Patented July 23, 1918.

Application filed April 17, 1918. Serial No. 229,210. Term of patent 3½ years.

To all whom it may concern:

Be it known that I, FRANK H. SCHAFFER, a citizen of the United States, residing at Providence, in the county of Providence, State of Rhode Island, have invented a new, original, and ornamental Design for a Brooch-Pin or Similar Article of Jewelry, of which the following is a specification, reference being had to the accompanying drawing, forming part thereof.

The figure is a face view of a brooch pin or similar article of jewelry showing my new design.

I claim:

The ornamental design for a brooch pin or similar article of jewelry, substantially as shown.

Signed at Providence, in the county of Providence, State of Rhode Island, this 11th day of April, 1918.

FRANK H. SCHAFFER.
